Charles F. Taylor, Chicago, Ill., assignor to Gibbs
& Company, a corporation of Illinois

Application July 16, 1935, Serial No. 57,664

Term of patent 3½ years

To all whom it may concern:

Be it known that I, Charles F. Taylor, a citizen of the United States, residing at Chicago, in the county of Cook and State of Illinois, whose post office address is c/o Gibbs and Company, 21 South Wabash Avenue, Chicago, Illinois, have invented a new, original, and ornamental Design for a Hair Drying Apparatus, of which the following is a specification, reference being had to the accompanying drawing, forming a part thereof.

Fig. 1 is a perspective view showing my new design;

Fig. 2 is a front elevational view of the same;
Fig. 3 is a top plan view of the same; and
Fig. 4 is an end elevational view of the same.
I claim:

The ornamental design for a hair drying apparatus as shown.

Signed at Chicago, county of Cook, State of Illinois, this 27th day of June, A. D., 1935.

CHARLES F. TAYLOR.
